UNITED STATES PATENT OFFICE.

CHARLES W. JONES, OF GRAND RAPIDS, MICHIGAN, ASSIGNOR TO THE JONES EASY INVALID LIFTER COMPANY.

DEVICE FOR LIFTING AND MOVING THE SICK.

SPECIFICATION forming part of Letters Patent No. 651,761, dated June 12, 1900.

Application filed June 26, 1899. Serial No. 721,930. (No model.)

To all whom it may concern:

Be it known that I, CHARLES W. JONES, a citizen of the United States, residing at Grand Rapids, in the county of Kent and State of 5 Michigan, have invented new and useful Improvements in Devices for Lifting and Moving the Sick, of which the following is a specification.

This invention has for its object to provide 10 a new and improved device or machine for conveniently lifting and easily moving sick persons wherein provision is made for conveying the person from place to place in a room or from one room to another. This object is accomplished in the manner and by the 15 means hereinafter described and claimed, reference being made to the accompanying drawings, in which—

Figure 1 shows a side elevation of my lifting-frame, together with the support or lifter upon which the patient is placed, also the turn-table or turning device whereby the patient can be turned in any direction while supported by the lifting and patient-supporting 25 frame. Fig. 2 shows an end elevation of that part of the frame which is placed at the foot end of the bed. Fig. 3 shows a plan view of the lifting-frame—the support upon which the patient is placed—with the turning device re- 30 moved. Fig. 4 shows a side elevation of the clutch which forms the joint in the supporting device, allowing one end of the supporting device to be raised and secured in any suitable position; and Fig. 5 shows a detail 35 view of the clutch, the parts being separated.

Similar letters refer to similar parts throughout the several views.

A shows a framework of the lifting and transporting device. This framework is constructed, preferably, of metal, and it should 40 be of such length as to allow the bed or cot on which the patient reclines to be placed between the two ends of this supporting-frame. The supporting-frame is placed upon casters, 45 (shown by A'). The frame is provided, preferably, with braces at the top and on either side. Two of these braces are shown by B B', they being secured by means of the thumb-nuts B' B', which thumb-nuts can be loosened 50 in order to place the frame into condition to

be folded into compact form. C and D show braces at the end of this frame, which end is preferably placed at the head of the bed or cot in use, and which end I will refer to as the "head" end of the lifting and supporting 55 frame. In order to strengthen this frame, I provide, preferably, three cross-pieces, which cross-pieces are shown in Fig. 1 by C', C'', and C'''. The ends of the frame are hinged or pivoted to the top of the frame at the point 60 shown by D'D''. The object of this construction is to allow the ends of the supporting-frame to be folded when the braces B and B have been disconnected at one end. I also provide, preferably, cross-braces at what I 65 term the "foot" end of the frame or that portion of the frame which passes over the foot of the bed or cot, which cross pieces or braces are shown by E and F in Figs. 1 and 2.

I provide, preferably, springs for the purpose of supporting the cords and pulleys which are used in raising the support. Those placed at the foot of the frame are shown in Fig. 2 by G G G G, and at the head of the frame I show the spring adjustment by G⁵, 70 and at the foot end or at the point of attachment of the ropes which support the foot end of the frame or support on which the patient rests I use similar springs, (shown in Fig. 1 by G⁴.) I also use pulleys supported by these 75 springs, which pulleys are shown in Fig. 2 by G' G' G' G'. G', G², and G³ are pulleys supported by the spring connections and which pulleys in turn support the lifting ropes or 80 cords hereinafter described.

It will be understood that Fig. 1 shows one side of the lifting-frame and that the other side is an exact duplicate of the view shown by Fig. 1.

H is a ratchet-wheel secured to the foot end 90 of the moving frame and provided with a crank K for operating the same. This ratchet-wheel H is rigidly secured to the roller or shaft J and is adapted to revolve with such roller, upon which roller the lifting-cords are 95 wound, as hereinafter described.

I is a pawl or dog adapted to engage with the ratchet-wheel, thereby stopping and retaining the ratchet-wheel in any desired position.

Whenever it is found necessary to lift the 100

patient and move the frame in order to transfer the patient from one room to another through a doorway, I provide what I call a "turn-table" or "turning device" composed of 5 upper and lower horizontal frames L and M, the upper frame being suspended by the lifting-cords through the medium of snaps Q, which engage holes in the cross-slats O. The lower frame M is centrally connected to 10 the upper frame L by a pivot or swivel N, and said lower frame M is connected with the lifting and patient-supporting frame T U, hereinafter described, by connections composed, as here shown, of springs R and R', 15 which engage with the cross-pieces O' O', and by the snaps S' S', as fully shown in Fig. 1.

P and P' show an adjusting device for taking up the ropes and cords in order to change the relative position of the support on which 20 the patient rests, as more fully described hereinafter.

The lifting and patient-supporting frame is composed, preferably, of a frame of sufficient size to entirely encircle the patient. 25 The plan view of this support is shown in Fig. 3, and the side view is shown in Fig. 1. The frame is preferably rectangular. In the side elevation T shows the longer or what I term the "foot" portion of this supporting- 30 frame and U the shorter or what I term the "head" portion. These two portions are attached together so as to allow the foot portion to remain horizontal, while the head portion can be raised to any required angle, 35 even to a right angle, if required, and can be locked in such position. This is accomplished by the mechanism shown more fully in Figs. 1, 4, and 5, which constitutes what I term a "clutch-hinge."

40 Y and V show two parts of the clutch-hinge having interlocking teeth d.

W shows a thumb-nut adapted to press together the two-part clutch-hinge, thereby locking the part U at any required angle to 45 the part T.

The lifting and patient-supporting frame is provided with canvas or other suitable fabric T', which is removably secured to the frame by any suitable devices.

50 It will be noticed that there are four cords which wind upon the shaft J. The two cords marked a a pass over the pulleys G² and are secured at O to what I term the "foot" end of the turning device, while the two cords b b

55 pass over the pulleys G³ and are secured to the end of the turning device nearest the head of the frame.

60 By operating the ratchet-wheel H and shaft J by means of the crank K the cords are wound upon the shaft J, and the movable support, together with the turning device, is raised and lowered.

65 The position of the cords a and b when attached directly to the support upon which the patient rests is shown by the dotted lines X X.

In order to place the patient properly upon

the support, the canvas (shown at T') is first placed under the patient while the patient is reclining upon the bed or cot. The rectangular frame T and U is then placed in position around the patient and the edges of the canvas secured thereto, as hereinbefore described. When properly secured, the patient rests upon the canvas and may be lifted by 70 means of the cords, pulleys, and shaft above described, it being understood that the two parts of the frame T and U are locked into position before the patient is lifted. When the patient is lifted upon the support, he rests 75 upon the canvas and may be raised to any required distance above the bed, and the framework A, with the patient thereon, may be removed to any part of the room and from one room to another in cases where the door will 80 allow. Whenever my lifting device is used in connection with a bedstead too high to enable the frame to stand over the head and foot, the turning device is used and the frame A is placed crosswise of the bed, while the lifting 85 frame is placed lengthwise of the bed. The patient can then be raised, and after the frame T U is lifted above the footboard said frame can then be turned in any required position in order to remove 90 the patient from room to room. A detached portion or flap (shown by U') is provided in the canvas T', the object of which is to enable the user of my lifting-frame to remove or partially remove the flap when it is desired to take the patient to the stool. Sometimes it will be found desirable merely to lift the patient, leaving him in a horizontal position. At other times it will be found useful to the patient to have the head portion of the 105 device or the part shown by U raised at an incline and locked in that position.

It will be noted that the patient can be transferred from place to place either in a horizontal position or in a sitting position 110 and that when the patient is returned to the bed or cot the canvas T' can be disengaged from the frame T U and then the frame removed and afterward the canvas.

The whole device may be used to advantage by making it a cot or bed of itself, as on top of the canvas can be placed a mattress or other suitable device upon which the patient may rest. In raising the part U of the frame to an angle the cords b are adjusted by means 115 of the attachment P'.

f and f' are screw-holes for attaching the clutch to the supporting-frame.

I have described my preferred form of upright frame and my preferred form of supporting-frame; but it will be evident that the general form of the frames may be modified and changed somewhat without departing from the spirit of my invention.

Having thus described my invention, what 130 I claim to have invented, and desire to secure by Letters Patent, is—

1. The combination of an upright frame, a shaft mounted thereon, lifting-cords con-

nected with the shaft, means for supporting and guiding the lifting-cords at the top of the frame, a turn-table suspended by said cords, and a patient-supporting frame suspended 5 from the turning part of the turn-table, substantially as described.

2. The combination of an upright frame, spring-suspended pulleys at the top of the frame, a shaft mounted on the frame, lifting-cords connected with the shaft and passing over said spring-suspended pulleys, a turn-table composed of two frames centrally swiveled together and the upper one connected with the lifting-cords, and a patient-supporting frame suspended from the lower turning frame of said turn-table, substantially as described.

3. The combination of a collapsible upright frame, casters supporting said frame, a revolving shaft, a plurality of cords each having one end attached to the said shaft, a turning device supported by the said cords, a lifting or supporting frame beneath the said turning device, a suitable connection be-

tween the said lifting-frame and said turning device.

4. The combination of an upright wheeled frame, a cord winding and unwinding shaft journaled thereupon, a plurality of lifting-cords connected with the shaft, cord support guides at the top of said frame, a turn-table composed of two horizontal, superimposed frames swiveled together at their center, devices detachably connecting said lifting-cords with the uppermost frame of said turn-table, a patient-supporting frame arranged below the turn-table, and a series of independent springs detachably connecting the lowermost frame of said turn-table with said patient-supporting frame, substantially as described.

In testimony whereof I have hereunto set my hand in presence of two subscribing witnesses.

CHARLES W. JONES.
